UNITED STATES PATENT OFFICE.

WILLIAM DANNENBERG, OF ELMORE, MINNESOTA.

LIFTING-JACK.

1,176,738.

Specification of Letters Patent. Patented Mar. 28, 1916.

Application filed April 24, 1914. Serial No. 834,166.

To all whom it may concern:

Be it known that I, WILLIAM DANNENBERG, a citizen of Germany, residing at Elmore, in the county of Faribault and State 5 of Minnesota, have invented certain new and useful Improvements in Lifting-Jacks, of which the following is a specification.

This invention relates to improvements in lifting jacks and its object is to produce a 10 device of this class particularly adapted for raising fence posts, raising pipes from wells, cisterns and the like.

With the foregoing and other objects in view the invention consists in the combination 15 and arrangement of parts to be herein-after fully described in the following specification, pointed out in the claim and illustrated in the accompanying drawings which form a part of said specification and in 20 which—

Figure 1 is front elevation of my improved lifting jack. Fig. 2 is a section on line 2—2 of Fig. 1 with part of the tackle in section. Fig. 3 is a section taken on line 25 3—3 of Fig. 1. Fig. 4 is a section taken on line 4—4 of Fig. 5. Fig. 5 is a section taken on line 5—5 of Fig. 1.

Like reference characters indicate corresponding parts throughout the several 30 views.

The reference numeral 1 indicates the base of the jack provided with feet 2 and to the base a block 3 is bolted as at 4 which block and base, respectively, are apertured 35 and recessed to receive the foot 5 of the screw 6 which is turned by a handle 7 fitting holes in the head 8.

Copies of this patent may be obtained for five cents each, by addressing the "Commissioner of Patents, Washington, D. C."

9 is the tackle formed with prongs 10, 10 through which clamps 11, 11 project that engage the work to be raised and said tackle 40 is recessed as at 12 to form a clearance for the tongs 13 which are adapted to grip the screws 6 to effect movement of the tackle through operation of the said screw.

Operation: The clamps 11, 11 are adjust- 45 ed about the work to be raised and rotation of the screw will raise the tackle and work. When the tackle has been raised into proximity with the head 8 said tackle may be lowered by disengaging the tongs from the 50 screw when the tackle may be permitted to move to the base block 3 and a new purchase upon the work obtained. This arrangement avoids the necessity of reversing the screw to lower the tackle. 55

What is claimed is:—

In a lifting jack, the combination with a base provided with a screw and means for rotating the same, of a recessed tackle, prongs formed integral with said tackle, op- 60 positely disposed manually operable clamps carried by said prongs and tongs disposed in the recessed portion of said tackle for re- leasable engagement with said screw.

In testimony that I claim the foregoing 65 as my own I have hereto affixed my signature in the presence of two subscribing witnesses.

WILLIAM DANNENBERG.
